UNITED STATES PATENT OFFICE.

SAMUEL W. WILSON, OF NEW YORK, N. Y.

SHIRT-COLLAR BUTTON.

SPECIFICATION forming part of Letters Patent No. 239,585, dated March 29, 1881.

Application filed October 12, 1880. (No model.)

To all whom it may concern:

Be it known that I, SAMUEL W. WILSON, of New York, in the county and State of New York, have invented certain new and useful 5 Improvements in Shirt-Collar Buttons and Shirt-Collars, of which the following is a specification.

Owing to the difficulty of making two shirt-collars of exactly the same size, and to the variation in their length which arises from different treatment in laundering, there oftentimes is such a discrepancy between the length of a shirt-collar and the shirt-band as to cause the collar to fit badly, and when too large to show the shirt-band.

15 The object of my invention is to obviate this difficulty and to provide for taking up or letting out a shirt-collar, to make it correspond with the shirt-band upon which it is worn.

20 To this end my invention consists in the combination, with a shirt-collar button having a shank for fitting in button-holes in the ends of a collar, of means independent of said shank for acting upon the ends of the collar adjacent to said button-holes, and serving to retain the 25 ends of the collar in different relations to each other.

In the accompanying drawings, Figure 1 is 30 a perspective view of a shirt-collar and collar-button embodying my invention. Fig. 2 is a side view of the button with the front plate or piece thrown outward. Fig. 3 is a side view of a button of modified form embodying my invention. Fig. 4 is a transverse section of 35 the same button shown in the previous figures, and illustrating a peculiar formation of the back plate. Fig. 5 is a perspective view of a shirt-collar and a button of modified form embodying my invention; and Fig. 6 is a perspective view of the same shirt-collar and button, showing the latter in a different position.

40 Similar letters of reference designate corresponding parts in all the figures.

Referring first to Figs. 1 and 2, A designates a shirt-collar, which may be of any desirable style and material, and which has an eyelet, *a*, in one end, in addition to and near an ordinary button-hole, *b*, and in the other end a series of eyelets, *c*, arranged in a row, and in 45 addition to and near an ordinary button-hole, *d*. A series of eyelets may be provided in each end of the collar.

B designates a collar button or stud of any appropriate material, having a flat shank or post, *e*, a round or other suitably-shaped post, 50 *f*, near the former, and a front plate or piece, *g*, hinged to said shank or post *e*, and capable of being turned down on the end of the post *f* or adjusted outward into a position parallel with the shank or post *e*. The shank or post *e* may be provided with a recess, *m*, for the reception of the edge of the front plate when said front plate is turned up.

If desirable, there may be combined with the shank or post *e* and front plate, *g*, a spring for 55 retaining the latter in position when turned down.

It may be preferable to combine with the front plate and post *f* a catch for fastening the front plate when turned down to the said post *f*. Such a catch may consist merely of a notch, *k*, in the post *f*, wherein the edge of the front plate can fit, and the edge of the front plate may be notched, as at *l*, to embrace the notch *k* in the post; but of course this is only 75 one of a number of ways in which such catch may be made.

The shank or post *e* is passed through the button-holes *b* and *d*, and the round post *f* passes through the eyelet *a* and through one 80 of the series of eyelets *c*, and thus retains the ends of the collar in position relatively to each other. If the collar is too long, the post *f* may be passed through one of the series of eyelets *c* farther from the extremity of the end of the 85 collar in which they are arranged, and when the collar is too short said post *f* may be passed through one of the series of eyelets *c* nearer to the extremity of the end of the collar in which they are arranged. Where only one end of 90 the collar is provided with a series of eyelets, the back button-hole, *h*, of the collar is preferably made to extend lengthwise of the collar, so as to allow of the slipping of the collar lengthwise, to admit of the adjustment of the 95 ends, when their relation is varied, to still occupy their proper position with respect to the center of a shirt-front. After the post *f* is passed through the eyelets the front plate of the stud is turned down over it. The back plate, *i*, of the button is preferably, in this example of my invention, hollowed out or cut off close to the post *f*, to prevent it from projecting undesirably above the shirt-band and col-

lar ends, and the portion contiguous to the shank or post *e* may be likewise hollowed out or cut away. I desire it to be understood that as the post *f* passes over or through an eyelet 5 or eyelets in the shirt-band, it prevents the shirt-collar from riding above the shirt-band.

I may provide the post *f* near its outer end with an annular groove, *j*, so that the outer end of the collar will fit therein and tend to be 10 precluded from pressing outward against the front plate, *g*, of the button. As the outer end of the collar bears against the front plate, *g*, of the button outside the shank or post *e*, it will tend to hold the front plate in the turned-down position, and as this groove *j* in the post 15 *f* tends to prevent the collar from pressing the front plate outward, the latter has a tendency to remain in its turned-down position.

Referring now to Fig. 3, the button there 20 shown is substantially the same as that previously described, except that its post *f* has a sharp point and is adapted to pierce the ends of collars having no eyelets. In this button no catch to fasten the front plate to the post 25 *f* is employed.

Referring to Figs. 5 and 6, I have there 30 shown a button substantially like those above described, except that its shank or post *e* is round, but provided with a head arranged like the head of a T, to afford adequate breadth for 35 properly hinging the front plate, *g*, to it. This button may be arranged with the shank or post *e* in the button-hole *b d*, and the post *f* lapping over the top edge of the collar ends, as shown in Fig. 5; or it may be arranged with 40 both the shank or post *e* and the post *f* passing through the button-holes *b d*, as shown in Fig. 6. In the former case the collar will be let out to its fullest extent, while in the latter 45 case the collar will be considerably tightened or taken in, as the two posts passing through the button-holes will cause the button-holes to lap more than will the one alone.

By my invention I provide in a simple and convenient manner for varying the length of a 45 collar to suit the length of a shirt-band, so that it will nicely fit the same. I also lessen the tendency of the collar to become accidentally unfastened.

I desire to remark that I do not confine myself to the post *f* as a means for acting upon the ends of the collar adjacent to the button-holes for fastening the same in position, as a clamp or other means may prove useful in lieu thereof. 50

What I claim as my invention, and desire to secure by Letters Patent, is—

1. The combination, with a shirt-collar button having a shank for fitting in button-holes in the ends of a collar, of means independent of said shank for acting upon the ends of said collar adjacent to the button-holes, and serving to retain the ends of said collar in different relations to each other, substantially as and for the purpose specified. 60

2. The combination, with a shirt-collar button having a shank or post with a front plate hinged thereto, of a second post, substantially as and for the purpose specified.

3. The combination, in a shirt-collar button, 70 of a back plate, the shank or post *e*, post *f*, with its groove *j*, and the binged front plate, *g*, substantially as and for the purpose specified.

4. The combination, in a shirt-collar button, 75 of the cut-away back plate, *i*, the shank or post *e*, the post *f*, and the front plate hinged to the shank or post *e*, substantially as and for the purpose specified.

SAML. W. WILSON.
